UNITED STATES PATENT OFFICE.

MOSES G. LANDSBERG, OF CHICAGO, ILLINOIS.

DESIGN FOR A BOTTLE.

SPECIFICATION forming part of Design No. 13,699, dated March 6, 1883.

Application filed December 7, 1882. Term of patent 3½ years.

To all whom it may concern:

Be it known that I, MOSES G. LANDSBERG, of Chicago, in the county of Cook and State of Illinois, have originated and invented a new and useful Design for Bottles; and I do hereby declare that the following is a full, clear, and exact description thereof, reference being had to the accompanying drawings, forming a part of this specification.

10 The object of my present invention is to provide a novel design for a bottle, which I denominate the "Sphinx;" and it consists in making the body of the bottle with four rectangular sides having arched tops, the alternate faces to receive a label or labels, and one of the other faces having in the glass the raised figures of a griffin, a sphinx, and a human-headed lion, placed above each other in the order named, while the opposite side contains a raised figure of a mortar and pestle over the letters "M. G. L." in monogram within a circle. The corners are rounded, columnar, and corrugated vertically, while the shoulder and neck of the bottle are shaped into a base and obelisk, on the sides of which are raised figures of birds, animals, and hieroglyphics.

15 In the accompanying drawings, Figure 1 is a side view of one of the figured sides of my bottle, and Fig. 3 represents another of the alternate sides containing the figures, while Fig. 2 shows one of the plain sides intended to receive a label.

20 Referring to the drawings, A is the bottle, which I call the "Sphinx," of which a repre-

25 sents one of the sides containing the raised figures, and b one of the other sides with the smooth face. The corners are rounded and columnar, and have regular parallel corrugations running from top to bottom, as shown at c. The shoulder of the bottle represents 30 the base d and pedestal e of the obelisk f, which forms the neck. The sides of the obelisk are covered with the raised figures and hieroglyphics.

35 Having thus described my design for a bottle, what I claim is—

40 1. The design for a glass bottle of which the body is four-sided, and on one of the alternate facets of which are raised figures of the sphinx, griffin, and human-headed lion, and the opposite side having the raised figure of a mortar and pestle above the letters "M. G. L." inclosed in a circle, the other two sides being plain to receive a label or labels, while the corners are rounded and corrugated, as shown and described.

45 2. The shoulder of the bottle shaped to represent the base and pedestal of an obelisk, which obelisk is formed by the neck of the bottle.

50 In testimony that I claim the foregoing as my own I affix my signature in presence of two witnesses.

M. G. LANDSBERG.
